UNITED STATES PATENT OFFICE.

CARL PETERSON, OF BRIDGEPORT, CONNECTICUT.

WRENCH.

1,405,432.

Specification of Letters Patent. Patented Feb. 7, 1922.

Application filed March 30, 1921. Serial No. 456,904.

To all whom it may concern:

Be it known that I, CARL PETERSON, a citizen of Finland, residing at Bridgeport, in the county of Fairfield and State of Connecticut, have invented certain new and useful Improvements in Wrenches, of which the following is a specification.

This invention relates to improvements in wrenches and its object is to provide a simple practical wrench provided with jaws which are jointly adjustable relative to the shank and which are adjustable also with relation to each other. A further object is to provide a wrench particularly adapted to work ordinarily difficult of access with the ordinary wrench. A further object is to provide a wrench that is cheap to manufacture, compact, positive and efficient in operation.

With the foregoing and other objects in view the invention consists in the combination and arrangement of parts to be herein-after fully described, pointed out in the appended claims and illustrated in the accompanying drawing which forms a part of this application and in which—

Fig. 1 is a view of my wrench in side elevation.

Fig. 2 is a longitudinal sectional view through the same.

Like reference characters denote corresponding parts in both views.

The reference numeral 1 denotes the shank which is formed with the flat end 2 and with the deep groove 3 extending from the base of said flat end 2 almost the entire length of the shank to the point 4. The said shank is formed with the diminished portion 5 thus forming the shoulder 6, and with the further diminished portion 7 thus forming the shoulder 8, the free end of the portion 7 being perforated to receive the stay pin 9.

A tubular rotary handle 10 is applied to the reduced portion of said shank, the open end of the handle embracing the shank portion 5 and riding against the shoulder 6, the opposite end of said handle being provided with the cap 11 perforated to permit passage therethrough of the free end of the portion 7 of the shank. The handle is formed interiorly with the raised threads 12 in engagement with the notched portions 13 formed in the flat pitman 14 disposed in the

grooved portion 3 of the shank and slideable longitudinally thereof. The pitman is formed with a shoulder 15 which may ride against the upper end of the handle 10, said pitman being pivotally connected by the pin 16 to the bifurcated portion 17 of the jaw 18, said bifurcated jaw portion 17 being fulcrumed upon the pin 19 carried by the flat shank portion 2.

Rotation of the handle 10 will slide the pitman 14 and so rock the jaw 18 upon its fulcrum. The jaw 18 is formed with the integral rack 20 upon which the relatively movable jaw 21, that cooperates with the jaw 18, is arranged, said jaw being movable over the rack by means of the thumb nut 22 connecting said members. Movement of the handle 10 moves the jaws 18, 21 together, two positions of the same being illustrated in the drawing. Movement of the thumb nut 22 moves the jaw 21 relative to jaw 18 for engagement with the work.

What is claimed is:—

1. In a wrench, a longitudinally grooved shank, a rotary handle at one end of said shank and formed interiorly with raised threads, a notched pitman slideable in the grooved portion of said shank and extending into said handle, the notches thereof receiving the threads of said handle, a jaw fulcrumed to said shank and connected to said pitman, a rack integral with said jaw, a second jaw slideable upon said rack, and a thumb nut connecting said second jaw and rack.

2. In a wrench, a longitudinally grooved shank, a rotary handle at one end of said shank and formed interiorly with raised threads, a notched pitman slideable in the grooved portion of said shank and extending into said handle, the notches thereof receiving the threads of said handle, a jaw fulcrumed to said shank and connected to said pitman, and a second jaw adjustably connected to said first named jaw.

3. In a wrench, a longitudinally grooved shank having one flattened end, a rotary handle at the opposite end of said shank and formed interiorly with raised threads, a perforated cap for one end of said handle, a notched pitman slideable in the grooved portion of said shank and extending through said handle and perforated cap, a stay pin in the free end of said pitman beyond said cap,

the notches in said pitman receiving the threads of said handle, a bifurcated jaw fulcrumed to the flattened end of said shank and connected to said pitman, a rack integral with said jaw, a second jaw perforated to receive said rack, and a thumb nut connecting said rack and second jaw.

In testimony that I claim the foregoing as my own I have hereto affixed my signature in the presence of two subscribing witnesses. 10
CARL PETERSON.
